UNITED STATES PATENT OFFICE.

JOHN FRANKLIN WHITMAN, OF ELKINS PARK, PENNSYLVANIA.

DESIGN FOR A CLOCK-CASING.

42,556.

Specification for Design.

Patented May 21, 1912.

Application filed February 16, 1911. Serial No. 609,073. Term of patent 14 years.

To all whom it may concern:

Be it known that I, JOHN FRANKLIN WHITMAN, a citizen of the United States, and a resident of Elkins Park, in the county of Montgomery and State of Pennsylvania, have invented a new, original, and ornamental Design for Clock-Casings, of which the following is a specification, reference being had to the accompanying drawings, forming part thereof.

Figure 1, shows an elevational view of a clock housing showing my new design, and Fig. 2, shows a side view thereof.

My design refers to a rectangular clock housing, showing a quarter-sawn oak effect, the face having a dial opening which is skirted by an egg-and-dart molding radiat-

ing from a plain circular bead. The outer edge is sloping to form a champ, embellished with a water leaf which extends outward from a plain bead or embossment. A flat fillet lies between the two beads or embossments, and this fillet at four points carries a spandrel ornament or scroll.

I claim:

The ornamental design for a clock casing as shown and described.

In testimony whereof I affix my signature, in presence of two witnesses.

JOHN FRANKLIN WHITMAN.

Witnesses:

A. TUHOLSKE,
THOMAS J. MURRAY, Jr.
